(57) **CLAIM**

The ornamental design for a shrubber cutting blade unit, as shown and described.

DESCRIPTION

FIG. 1 is a front perspective view of a shrubber cutting blade unit in combination with a power tool housing;

FIG. 2 is a front perspective view of a shrubber cutting blade unit;

FIG. 3 is a left side view of a shrubber cutting blade unit;

FIG. 4 is a right side view of a shrubber cutting blade unit;

FIG. 5 is a top view of a shrubber cutting blade unit;

FIG. 6 is a bottom view of a shrubber cutting blade unit;

FIG. 7 is a front view of a shrubber cutting blade unit; and,

FIG. 8 is a rear view of a shrubber cutting blade unit.

The broken line showing of a power tool housing is for illustrative purposes only and forms no part of the claimed design.
